STABILIZER FOR GLIDER SEATS

Filed Jan. 16, 1932

INVENTOR
William F. Williams,
BY *W. F. Williams*

UNITED STATES PATENT OFFICE

WILLIAM F. WILLIAMS, OF ROCHESTER, NEW YORK, ASSIGNOR TO QUALITY MATTRESS COMPANY, OF ROCHESTER, NEW YORK, A CORPORATION OF NEW YORK

STABILIZER FOR GLIDER SEATS

Application filed January 16, 1932. Serial No. 587,052.

This invention relates to improvements in glider seats particularly of a type having a stabilizer connected thereto.

An object of this invention is to provide a stabilizer for a glider which will permit the free swinging or gliding movement of the seat and at the same time operate to keep the seat in a central position with respect to the upright end portions of the main frame or base.

A further further object of this invention is to provide a glider seat having a stabilizer connected therewith in such a manner that portions of the structure will not come in contact with the user of the glider.

Another object of this invention is to provide a stabilizer simple and inexpensive of manufacture that may be easily connected with glider seat devices.

Other objects of this invention will appear from the following detailed description of the device and as disclosed in the single sheet of drawing which is herewith made a part of this application.

In the drawing:—

Figure 1 is a top plan view of the glider seat and stabilizer.

Fig. 2 is a front sectional elevational view of Fig. 3 taken along line 2—2.

Fig. 3 is a sectional view of Fig. 1 taken along line 3—3.

In the preferred form of this invention numeral 1 designates the main or base frame of the glider which may be made of any suitable material, while numeral 2 designates the end portions which normally extend upwardly from the outer ends of the main or base frame 1, as clearly disclosed in Fig. 2.

The main frame 1 of the glider may include a plurality of parallel members 3 and 4 extending longitudinally of the base frame.

The glider seat 5 is adapted to be swung in any suitable manner from the cross member 6 of the upright end portions 2 by means of chain portions 7, or otherwise as may be desired. The seat 5 is ordinarily constructed having a plurality of cross members 8 spaced apart and adapted as a support for some suitable type of seat mattress.

In order to permit of free swinging or glid-

ing movement of the seat 5 and at the same time provide a means for bringing the seat back to center with respect to the upright end portions 2 it is preferred in this invention to provide two upwardly and centrally inclined members 9 and 10 made of any suitable material, the outer ends of the members 9 and 10 being pivotally mounted, as at 11 and 12 to base frame members 13 and 14, the base frame members 13 and 14 being suitably connected with the frame elements 3 and 4, and braced as at 15 and 16, so as to provide the required pivoting member in cooperation with the rod portions 9 and 10. The inner ends of the rods 9 and 10 are preferably provided with spring members 17 and 18 for resilient attachment to a cross member 19 of the movable seat 5.

As clearly set forth in the above description it is apparent that the stabilizer will function to permit the free swinging of the movable seat as suspended from the chain portions and at the same time the stabilizer rods 9 and 10 as arranged will operate to bring the seat back to normal position with respect to the upright ends of the main frame, it being understood that any suitable resilient and pivoting means may be utilized. By virtue of the suspension and stabilizing means described the ends of the seat and back so are maintained out of engagement with the end 2 of the supporting structure.

It will be understood, that without departing from the spirit or scope of the invention, the stabilizer device claimed herewith may be adapted to gliders or the like of various types different from that described.

What is claimed is:

A glider seat comprising end pieces, a base to which the end pieces are connected and including slightly elevated longitudinal parallel members and transverse cross pieces connecting the same adjacent the ends thereof, a seat member swingingly suspended from the end pieces over the base and including a rigid transverse cross piece arranged substantially intermediate the ends thereof and above the plane of the aforesaid transverse cross pieces, and a stabilizer comprising two bars each pivoted at its outer end to the re-

spective transverse cross piece of the base and resilient elements connected to the transverse cross piece of the seat member and to the inner ends of said bars whereby to prevent undue endwise movement of the seat during
5 swinging movement thereof.

In testimony whereof I have hereunto set my hand this 28th day of December, 1931.

WILLIAM F. WILLIAMS.
